(57) **CLAIM**

The ornamental design for an applicator, as shown and described.

DESCRIPTION

FIG. 1 is an enlarged perspective view of an embodiment of an applicator embodying the new design.

FIG. 2 is a front view of the design shown in FIG. 1;
FIG. 3 is a right side view of the design shown in FIG. 1;
FIG. 4 is a back view of the design shown in FIG. 1;
FIG. 5 is a left side view of the design shown in FIG. 1;
FIG. 6 is a top view of the design shown in FIG. 1; and,
FIG. 7 is a bottom view of the design shown in FIG. 1.

These figures are lined for transparency and comprise stippling to claim a feature inside a transparent housing.
Broken lines shown in the figures described above form the bounds of the claimed design but do not form part of the claimed design.
